GRADE LINE MARKER

Aaron G. Reynolds, Rte. 1, Box 250, McAllen, Tex.
Filed Jan. 15, 1958, Ser. No. 709,115
17 Claims. (Cl. 37—170)

This invention relates generally to apparatus for use in the leveling of land to grade. More particularly, it relates to improved apparatus for marking the grade to which the land is to be leveled.

The customary practice in land leveling is to at least approximately level the land and then, by means of a large number of grade stakes, mark the grade for finishing. Ordinarily, one man sights through a leveling instrument to direct another in driving the stakes at spaced apart locations over the area to be leveled, or the stakes are grade-marked by one of various methods pursuant to elevation readings taken at said locations. Both of these operations are tedious and time-consuming. Also, it is relatively easy for these stakes to be uprooted, or at least jarred out of position, during the finishing process so that they do not represent the true grade. Still further, these stakes, or the grade-indicating markings thereon, are visible to the operator of earthmoving equipment for a relatively short distance.

An object of this invention is to provide apparatus for marking the grade of a land area to be leveled without the use of grade stakes or the like.

Another object is to provide apparatus for marking the grade of a land area to be leveled with means which are easier to establish, more permanent and visible for greater distances than the conventional grade stakes or grade markings thereon.

These and other objects are accomplished, in accordance with the present invention, by means of a grade line marker which comprises a frame movable over the ground level, means on the frame for selectively raising or lowering a row of the ground as the frame is moved thereover, and gauge means for determining the elevation of said row with respect to a point distant from the frame. With such apparatus, it is possible for an instrument man to sight upon the gauge means and thus indicate to an operator of the grade line marker the extent to which the row is to be raised or lowered. The operator may, in turn, selectively control suitable actuating mechanism for raising or lowering the row in accordance with the instrument man's directions. Thus, it is possible to mark the land area along lines defined by the raised or lowered rows which serve the same purposes as grade stakes, without the disadvantages attendant thereto.

More particularly, the means for selectively raising or lowering a row comprises a gathering member and a digging member supported on the frame, and means for moving each of said members below the ground level for raising and lowering a row. In a preferred embodiment of the invention, the digging member is disposed rearwardly of the gathering member, the moving means is adapted to raise the digging member above the ground level for leveling to grade the row raised by said gathering member, and the gauge means comprises a level rod movable with the gathering member.

A further object of the invention is to provide a grade line marker of simplified construction and operation, and more particularly one in which the gathering and digging members are moved between row raising and lowering positions by means of only a single actuator.

This latter object is accomplished by a grade line marker in which the gathering member and digging member are disposed on opposite ends of a support mounted for pivoting about an axis transverse to the direction of movement of the frame, and an actuator is provided for

2

swinging the support about its pivotal mounting to move each of said members between positions above and below the ground level. Preferably, the gathering member and digging member are carried by longitudinally spaced apart parallel arms pivotally connected to opposite ends of a pair of vertically spaced apart parallel bars pivotally mounted on the frame to form a parallelogram support for maintaining the members in a fixed relation with respect to the ground level during all movements and in all positions of the support.

A still further object is to provide a grade line marker of the character above described in which the raised row is compact.

For the above purposes, the grade line marker of the present invention includes another member for smoothing and compressing the top of the row raised by the gathering member prior to its being leveled by the digging member. This other member comprises a blade or the like mounted on the frame for pivoting about a transverse axis, and a part on the parallelogram support engageable with this other member upon movement of the gathering member below the ground to maintain said other member at a level above the digging member.

In the drawings, wherein like reference characters designate like parts:

FIG. 1 is a side elevational view, partly in section, of a grade line marker constructed in accordance with the present invention and in the process of raising a row to grade;

FIG. 2 is an elevational view of the grade line marker of FIG. 1 in a neutral position;

FIG. 3 is a similar view of the grade line marker, but in the process of lowering a row;

FIG. 4 is a front sectional view of the grade line marker, as seen along broken line 4—4 of FIG. 2; and

FIG. 5 is a rear elevational view of the grade line marker, as seen along broken line 5—5 of FIG. 2.

Referring now in detail to the above-described drawings, the grade line marker comprises a frame 10 which includes a body 11 supported from a rectangular base 12 by means of lateral braces 13 or the like. The base is supported above ground by means of downwardly and outwardly extending legs 14 and 15 connected to the forward and rearward corners thereof, respectively. The front legs 14 are, in turn, supported from legs 17 connected to the body 11, and an auxiliary leg 18 forms a brace between each of the rear legs and the base. A runner 16 is connected to the lower end of each of the legs 17 and 14 to support the body of the frame at a fixed elevation above the ground level G as the frame is moved thereover.

A yoke 19 is pivotally connected to the forward end of the body 11 for attachment to a tractor 20, as shown in broken lines in FIG. 1, or other vehicular means for towing the frame forwardly from right to left. To facilitate such movement, the forward or leftmost end of each of the runners 16 is turned upwardly, as shown at 21. Alternatively, means may be provided on the frame itself for moving it over the ground.

A support 24 for a gathering member 22 and a digging member 23 includes a pair of parallel bars 25 mounted by pins 26 on opposite sides of the body 11 for pivoting about vertically spaced apart transverse axes. Parallel arms 27a are pivotally connected to the forward ends of the bars 25 by pins 28a and 29a, and an arm 27b parallel to arms 27a is pivotally connected to the rearward ends of the bars 25 by pins 28b and 29b. The gathering and digging members are secured to the lower ends of the arms 27a and 27b, respectively, so that they are moved between positions above and below the ground level G as the bars 25 are swung about the pivot pins 26. More particularly, the parallelogram support above

described maintains the arms upright during such swinging so that the gathering and digging members are maintained in a fixed relation to the ground level in all their positions.

As best shown in FIG. 4, the gathering member comprises a pair of plates 30 which are rearwardly convergent and spaced apart at their rearward ends to provide a gradually decreasing passage therebetween. The lower edges 31 of the plates are turned inwardly to facilitate cutting of the soil as the plates are lowered and moved forwardly beneath the ground level, as shown in FIG. 1. The soil so cut is then compressed by the convergent plates so that an unfinished row thereof flows through the passage therebetween and is raised above the ground level. The lower ends of the arms 27a are bent for securement to the outside of the plates 30 by means of bolts 32.

It will be understood that while other gathering means may be provided for raising a row of the ground over which the frame is moved, the gathering member 22 constitutes a simplified and effective device for this purpose.

The digging member 23 comprises a pair of plates 33 which intersect at their forward edges and are rearwardly divergent. The lower edges 34 of these plates are turned outwardly to facilitate plowing of the soil as such plates are lowered and moved forwardly beneath the ground level to lower a row to the grade L in FIG. 3. The lower end of the arm 27b is secured to the inner sides of the plates 33 by means of bolts 35 and straps 36.

It will be understood that other digging devices may be used for raising a row of the ground over which the frame is used. However, as in the case of gathering member 22, the digging member 23 is preferred due to its simplicity of construction.

More particularly, it will be noted that the arm 27b supports the digging member 23 rearwardly of the gathering member 22 so that its cutting edges 34 will level the top of the row raised by the gathering member to a grade R, as shown in FIG. 1. It will also be noted that, in the neutral position of FIG. 2, the lower cutting edges of each of the gathering member and digging member are disposed substantially flush with the ground level G so that the grade line marker may be moved over the ground without in any way altering the grade. This arrangement also enables the rows to be raised or lowered to a maximum range of elevations.

An actuator 37 for swinging the support between positions to move each of the gathering member and digging member above and below the ground level G comprises a cylinder 38 pivotally connected to the body 11 and a piston rod 39 pivotally connected to the leftmost pin 28a and having a piston thereon (not shown) sealably slidably within the cylinder. Ports 40 and 41 are provided in the cylinder to admit and exhaust hydraulic fluid to opposite sides of the piston in order to retract or extend the piston rod 39 in a well known manner. Thus, upon the introduction of hydraulic fluid into the port 41 and exhaustion of such fluid from the port 40, the piston rod is retracted to swing the support in a counterclockwise direction, thereby lowering the gathering member and raising the digging member. On the other hand, the introduction of hydraulic fluid into the port 40 and exhaustion thereof from the port 41 will extend the rod to lower the digging member and raise the gathering member. Obviously, such hydraulic control enables an operator to raise and lower the gathering and digging members to desired elevations as well as to maintain them in any desired position.

A level rod 42 having suitable graduations thereon is secured by bolts 43 or the like to the rear side of the rearward arm 27b. A target 44 is vertically adjustable along the rod 42 and may be brought into line of sight 45 by suitable operation of the actuator 37. Thus, as previously mentioned and as will be explained more

fully hereinafter, an instrument man may direct the operator of the grade line marker in raising or lowering a row of ground level G to a desired elevation by bringing the target into the line of sight.

5 A curved blade 46 is secured to the lower end of a parallelogram type support 47 on the body 11 to dispose its lower edge 48 just rearwardly of the passage through gathering member 22 and forwardly of digging member 23. A stop part 49 is located on the support 47 in a position to prevent the lower edge 48 from dropping beneath a predetermined elevation with respect to the ground level G. An arm 50 of the parallelogram support 47 extends rearwardly thereof for engagement with another arm 51 secured to and extending forwardly of the rearward support arm 27b. These two arms 50 and 51 are so arranged as to prevent the lower edge of the smoothing blade 46 from dropping below a point just above the lower cutting edge 34 of the digging member when the gathering member is lowered beneath the ground level for raising a row.

As will be understood from FIGS. 1 to 3, this blade will compress and smooth off the top of the unfinished row of ground which has been raised by such gathering member prior to the leveling of such row to grade by 25 the cutting edge of the digging member. Obviously, this same function may be performed by rollers or other equivalent means.

To illustrate the use of the above-described grade line marker, it will be assumed that the marker is disposed 30 on an area of land which is to be marked for grading and that a leveling instrument has been set up at a point distant from the marker. In accordance with methods well known in the art, the man operating the instrument may calculate the elevation of its line of sight. Inasmuch as 35 the vertical distance between the cutting edge 34 of the digging member 23 and any point on the level rod 42 is known, the instrument man may indicate to the operator of the marker the point at which the target 44 is to be fixed on the level rod 42 in order to raise or lower a row to grade. Thus, for example, if the line of sight is at an elevation of 50.0 feet and the desired grade is 45.0 feet, the target will be set at a point on the level rod which is 5.0 feet above the cutting edge 34.

This setting of the target may raise it or lower it above 45 or below the line of sight, respectively, depending on the elevation of the ground level upon which the marker is disposed. At any rate, the instrument man directs the operator of the marker in bringing the target into the line of sight so that, at the outset of the marking 50 operation, either of the gathering or digging members may be below the ground level.

By way of example, let it be assumed that the elevation of the ground level G is greater than 45.0 feet. In this case, when the target is brought into the line of sight, the digging member 23 is lowered beneath the ground level, as shown in FIG. 3, so as to lower a row of the ground over which the frame is moved. However, in so moving, the frame may traverse ground which lowers gradually and, more particularly, which falls beneath an 60 elevation of 45.0 feet. In this case, the instrument man, upon seeing that the target dips beneath the line of sight, will direct the operator of the grade line marker to raise the target and thus the lower edge 34 of the digging member. In practice, the instrument man will be in continuous communication with the operator of the marker so that the digging member is raised and lowered substantially simultaneously with changes in the elevation of the ground level.

From the foregoing it will be seen that this invention is one well adapted to attain all of the ends and objects hereinabove set forth, together with other advantages which are obvious and which are inherent to the apparatus.

It will be understood that certain features and sub-combinations are of utility and may be employed without

reference to other features and subcombinations. This is contemplated by and is within the scope of the claims.

As many possible embodiments may be made of the invention without departing from the scope thereof, it is to be understood that all matter herein set forth or shown in the accompanying drawings is to be interpreted as illustrative and not in a limiting sense.

The invention having been described, what is claimed is:

1. A grade line marker, comprising a frame movable over the ground level, a gathering member and a digging member supported on the frame, force-transmitting means on the frame for moving each of said members below the ground level so as to selectively raise and lower a row of the ground as the frame is moved thereover, and gauge means for enabling a person to determine the elevation of said row from a point distant from the frame.
2. A grade line marker, comprising a frame movable over the ground level, a support pivotally mounted on the frame for swinging about an axis transverse to the direction of movement of the frame, a gathering member on the support to one side of its pivotal mounting and a digging member on the support to the opposite side of its pivotal mounting and disposed rearwardly of said gathering member for leveling the top of the row raised by the gathering member, means for swinging the support about its pivotal mounting for moving each of said members between positions above and below the ground level so as to selectively raise or lower a row of the ground as the frame is moved thereover, and gauge means for enabling a person to determine the elevation of said row from a point distant from the frame.
3. A grade line marker of the character defined in claim 2, wherein said gauge means comprises a level rod on the support.
4. A grade line marker of the character defined in claim 2, including another member supported on the frame forwardly of the digging member for smoothing and compressing the top of the row raised by the gathering member.
5. A grade line marker of the character defined in claim 4, including means on the support to maintain said smoothing and compressing member at a level above the digging member when the gathering member is moved below the ground.
6. A grade line marker, comprising a frame movable over the ground level, a pair of parallel bars mounted on the frame for pivoting about vertically spaced apart axes extending transversely to the direction of movement of the frame, parallel arms pivotally connected to opposite ends of the bar to form a parallelogram therewith, a gathering member on one arm, a digging member on the other arm and disposed rearwardly of said gathering member for leveling the top of the row raised by the gathering member, means for swinging the bars about said axes for moving each of said members between positions above and below the ground level so as to selectively raise or lower a row of the ground as the frame is moved thereover, and gauge means for enabling a person to determine the elevation of said row from a point distant from the frame.
7. A grade line marker of the character defined in claim 6, wherein said gauge means comprises a level rod on the arm supporting the digging member.
8. A grade line marker of the character defined in claim 6, including another member for smoothing and compressing the top of the row of ground raised by the gathering member prior to its being leveled by the digging member, means mounting the other member on the frame for pivoting about a transverse axis, and a part on the parallelogram engageable with the other member upon movement of the gathering member below the ground to maintain said other member at a level above the digging member.
9. A grade line marker, comprising a frame movable over the ground level, a support mounted on the frame, a gathering member and a digging member on the support, means for moving the support to move each of said members in opposite directions between positions above and below ground level so as to selectively raise or lower a row of the ground as the frame is moved thereover, and gauge means for enabling a person to determine the elevation of said row from a point distant from the frame.
10. A grade line marker of the character defined in claim 9, wherein said digging member is disposed rearwardly of said gathering member for leveling the top of the row raised by the gathering member.
11. A grade line marker of the character defined in claim 9, wherein said support is pivotally mounted on the frame, and said gathering and digging members are mounted on opposite sides of the pivotal mounting of the support.
12. A grade line marker of the character defined in claim 9, including another member having a lower edge for smoothing and compressing the top of the row raised by the gathering member, and means for raising the lower edge of said other member above the level of the row to be raised in response to movement of said gathering member below ground level.
13. A grade line marker, comprising a frame movable over the ground level, a gathering member and a digging member supported on the frame with the digging member disposed rearwardly of the gathering member, means for moving each of said members below the ground level so as to selectively raise or lower a row of the ground as the frame is moved thereover and for moving the digging member above ground level for leveling the top of the row raised by the gathering member, gauge means for enabling a person to determine the elevation of said row from a point distant from the frame, another member having a lower edge forwardly of the digging member for smoothing and compressing the top of the row of the ground raised by the gathering member, and means for raising the lower edge of said other member above the lower edge of the digging member upon moving the gathering member below ground level.
14. A grade line marker, comprising a frame movable over the ground level, a gathering member and a digging member supported on the frame, means for moving each of said members below the ground level so as to selectively raise or lower a row of ground as the frame is moved thereover, another member having a lower edge for smoothing and compressing the top of the row raised by the gathering member, means for raising the lower edge of said other member above the level of the row to be raised in response to movement of said gathering member below ground level, and gauge means for enabling a person to determine the elevation of said row from a point distant from the frame.
15. A grade line marker, comprising a frame movable over the ground level, a gathering member and a digging member supported on the frame with the digging member disposed rearwardly of the gathering member, means for moving each of said members below ground level so as to selectively raise and lower a row of the ground as the frame is moved thereover and raising the digging member above the ground level for leveling the top of the row raised by the gathering member, and gauge means for enabling a person to determine the elevation of said row from a point distant from the frame.
16. A grade line marker of the character defined in claim 15, wherein said gauge means comprises a level rod movable with the digging member and having a target adjustably mounted thereon.
17. A grade line marker, comprising a frame movable

over the ground level, a gathering member and a digging member supported on the frame, force-transmitting means on the frame for moving the gathering and digging members vertically with respect to the ground level so as to selectively raise or lower a row of the ground as the frame is moved thereover, another member yieldably supported on the frame and having a lower edge positioned to smooth and compress the top of the row raised by the gathering member, means responsive to movement of the digging member for raising the lower edge of said other member to at substantially the same level as the lower edge of said digging member, and gauge means enabling a person to determine the elevation of said row at a point distant from the frame.
